UNITED STATES PATENT OFFICE.

CHESTER L. PEPPER, OF CHELSEA, MASSACHUSETTS, ASSIGNOR TO SCHUTTE & KOERTING COMPANY, OF PHILADELPHIA, PENNSYLVANIA, A CORPORATION OF PENNSYLVANIA.

SPRAY-NOZZLE.

1,205,563.

Specification of Letters Patent. Patented Nov. 21, 1916.

Application filed November 29, 1911. Serial No. 668,015.

To all whom it may concern:

- Be it known that I, CHESTER L. PEPPER, a citizen of the United States, residing at Chelsea, county of Suffolk, and State of Massachusetts, have invented certain new and useful Improvements in Spray-Nozzles, fully described and represented in the following specification and the accompanying drawings, forming a part of the same.
- 10 This invention relates to a spray nozzle of that class in which the liquid in passing through the nozzle is given a spiral or advancing rotary motion by means of spiral vanes or blades located within the nozzle.
- 15 The object of the invention is to provide an improved nozzle of this kind of simple construction and efficient in operation and whereby a spray of more solid, rather than hollow, conical form is secured.
- 20 A further object is to provide a nozzle which is adjustable for different spray angles and for securing the admixture of air with the jet before it leaves the nozzle or for a side discharge of water in fine jets.
- 25 The invention aims especially to provide a spray nozzle which shall show high efficiency when used for spray cooling of water and other liquids.
- 30 Nozzles made in accordance with the invention will be equally efficient when used for other purposes to which they are adapted, and they may be applied to a great variety of uses, for some of which, however, it may be desirable to omit in the construction of the nozzles certain features of the invention.
- 35 The accompanying drawings show a nozzle construction to embody the various features of the invention in the preferred form.
- 40 In said drawings:—Figure 1 is a central longitudinal section of the nozzle except that the spiral vanes for imparting rotary motion to the fluid are shown as they would appear in elevation. Fig. 2 is a view of the 45 discharge or tip end of the nozzle showing the same partly in side elevation and partly in central longitudinal section and with the tip piece in a different position of adjustment from that shown in Fig. 1. Fig. 3 is a cross sectional view taken on line 3 of Fig. 1.
- 45 Referring to the drawings, the nozzle tube as shown is made up of a cylindrical portion or body 10, and a tapered front portion 50 or nose piece 11 which is detachable from
- the body 10, as by having a screw thread connection therewith, to give ready access to the interior of the nozzle. Within the nozzle tube there are a plurality of spiral vanes 12 formed to leave an unobstructed axial path or channel 13 for the water or other liquid. These vanes in the preferred construction shown are located within the cylindrical body portion 10 and are cast or otherwise formed integral therewith, extending from the side wall inward and ending short of the axial line so that their inner edges extend spirally about a central open space which forms an unobstructed path or channel for the free movement of the liquid. 60 The vanes serve to give the advancing liquid the desired rotary or spiral motion, which, the velocity being greatly increased as the liquid passes through the contracted nose piece, causes the liquid as it leaves the nozzle mouth to break into a spray which advances from the nozzle in the form of a cone; and the unobstructed central channel around which the vanes curve allows the central portion of the stream of liquid to move 70 faster than the surrounding portions which encounter the vanes, and so insures a solid mass of liquid in the tip portion of the nozzle with the result that the spray advances from the nozzle in the form of a cone which is solid or substantially so as distinguished from a hollow conical spray such as is produced by a nozzle having the spiral vanes mounted around a central spindle. 75
- The nozzle has a tip 15 which is adjustable for varying the spray angle. It is preferably formed to provide a flaring mouth as shown, which should be at its narrowest point of slightly greater diameter than the internal diameter of the end or narrowest point of the nose piece, and it is secured to the nose piece by an interiorly threaded flange 16 which screws on to the threaded end of the nose piece, so that the tip may be adjusted to stand off more or less beyond the 80 end of the nose piece by being turned in one direction or the other thereon. When the tip is adjusted to a position close to the end of the nose, a comparatively wide spreading spray is produced; and as the tip is set 85 farther off from the end of the nose, a narrower and longer, or higher, spray results. The space between the end of the nose piece and the shoulder at the inner end of the flange of the tip forms an annular passage 90
- 95
- 100
- 105
- 110

17 which as shown opens into the tip portion or mouth of the nozzle in the direction of the movement of the liquid and which is open to the atmosphere through a series of openings 18 or through the openings 18 and a second series of openings 19 according to the adjustment of the tip. When the tip is screwed in to the position or about the position shown in Fig. 1, the opening of the passage 17 is narrowed down so that the passing liquid tends to create a partial vacuum in the passage whereby air entering the passage through the openings 18 is sucked into the liquid as it issues from the nozzle. The air so sucked into the jet causes the spray to break up into finer particles and secures a more intimate mixture of air with the sprayed liquid. This is of advantage in many uses of the nozzle, as for example, and especially, when the nozzle is used in spray cooling of water. In nozzles used for fountains, also, this feature has the advantage of causing the jet or spray to appear much whiter than without the sucked in air. When the tip is screwed out to a position as shown in Fig. 3, for example, the passage 17 is widened and the air suction is broken and water will then enter the passage and escape in fine jets through the openings 18 and also through the openings 19 which with the tip in this position are open to the passage.

It is to be understood that the invention is not to be limited to the exact construction shown and to which the foregoing description has been largely confined, but that it includes changes therein and modifications thereof within the claims.

What is claimed is:—

1. A spray nozzle having a spray producing spiral vane for imparting rotary motion to the advancing fluid whereby the fluid is caused to break into spray as it leaves the nozzle, said vane extending inward from the nozzle wall and ending short of the axis of the nozzle so as to leave an unobstructed axial channel or path to allow the central portion of the stream of liquid to advance faster than the surrounding portion said axial channel or path being defined by the edge of the vane and being in open communication with the surrounding space through which the vane extends, and having a velocity-increasing unobstructed tapering channel beyond the spiral vane.

2. A spray nozzle having a plurality of intercoiling spray producing spiral vanes for imparting rotary motion to the advancing fluid whereby the fluid is caused to break into spray as it leaves the nozzle, said vanes extending inward from the nozzle wall and ending short of the axis of the nozzle so as to leave an unobstructed axial channel or path to allow the central portion of the stream of liquid

to advance faster than the surrounding portion, said axial channel or path being defined by the edges of the vanes and being in open communication with the channels between the veins, and having a velocity-increasing unobstructed tapering channel beyond the spiral vanes. 70

3. A spray nozzle having a spray producing spiral vane for imparting rotary motion to the advancing fluid whereby the fluid is caused to break into spray as it leaves the nozzle, said vane extending inward from the nozzle wall and ending short of the axis of the nozzle so as to leave an unobstructed axial channel or path to allow the central portion of the stream of liquid to advance faster than the surrounding portion, said axial channel or path being defined by the edge of the vane and being in open communication with the surrounding space through which the vane extends, and having a velocity-increasing unobstructed tapering channel beyond the spiral vane, and a suction inlet for admitting air at a point near the mouth of the nozzle. 80 90

4. A spray nozzle having a flaring mouth, an air suction inlet for admitting air to the jet at a point just beyond the point of narrowest cross-section of the nozzle, and means for imparting spray producing rotary motion to the fluid advancing through the nozzle tube whereby the fluid is caused to break into spray as it leaves the nozzle. 95

5. A spray nozzle comprising a nozzle tube having a tapering nose portion, and a tip piece adjustable toward and from the end of the nozzle tube to vary the spray angle and formed to provide a passage between it and the end of the nozzle tube to serve as an air suction passage when the tip piece is close to the end of the nozzle tube and as a discharge passage when the tip piece is moved away from the end of the nozzle tube. 100 105

6. A spray nozzle comprising a nozzle tube having a tapering nose portion and provided with means for imparting rotary motion to fluid advancing therethrough, and an adjustable tip shaped to provide a passage between it and the end of the nozzle tube to serve as an air suction passage when the tip is adjusted to a position close to the end of the nozzle tube and as a discharge passage when the tip is moved away from the end of the nozzle tube. 110 115 120

7. A spray nozzle having a tapering nozzle tube, and a tip formed to provide a flaring nozzle mouth of a diameter at its narrowest point slightly greater than the internal diameter of the end or narrowest point of the nozzle tube, said tip being secured to the end of the nozzle by means of a threaded socket flange screwed onto the threaded end of the nozzle tube whereby the tip may be adjusted toward and from 125 130 135

the end of the nozzle tube and having openings to the atmosphere from the space between the end of the nozzle tube and the tip to serve as air suction inlets when the tip is close to the end of the nozzle tube and as discharge outlets when the tip is adjusted to a position farther away from the end of the nozzle tube.

In testimony whereof, I have hereunto set my hand, in the presence of two subscribing witnesses.

CHESTER L. PEPPER.
